TELEPHONE SYSTEM.

David Adam Christian, Batley, and William Henry Joseph Dibben, Dewsbury, England, assignors to Siemens Brothers & Co. Limited, Westminster, London, England, a British company

Application November 30, 1942, Serial No. 467,328
In Great Britain January 7, 1942

12 Claims. (Cl. 179—18)

The present invention relates to telephone systems and more particularly to automatic systems in which there are main exchanges and satellite or sub-exchanges and in which calls from a satellite or sub-exchange to be completed locally or in an adjacent exchange are made without passing through the main exchange.

In a system of this kind a junction to the main exchange is automatically taken into use whenever a call is originated at a satellite exchange and discriminating apparatus is employed the function of which is to determine the destination of the call as soon as possible and release any route that has been seized or prepared but will not be required for use on the call.

In order that a call to a subscriber connected to a satellite exchange may be set up from any station by always dialling the same number it is usual when the calling station is connected to the same satellite exchange as the called line or to an adjacent exchange to absorb one or more digits as the full number of digits will not normally be required for the setting up of such a call. A selector, therefore, having responded to a digit that is to be absorbed is required to release and be in a condition to respond to another digit before the expiry of the inter-train pause. With some types of two-motion switches, for instance those that are released by a continued rotary motion followed by a vertical and then a backward rotary movement the inter-train pause may not be long enough to ensure complete release of the switch in all cases during the time available.

The present invention is directed to means whereby this disadvantage may be overcome with a view to a more certain operation of the selecting switch. Accordingly, in this invention a selector which has been taken into use and has responded to a digit which is to be absorbed is allowed to release in its own time, the next digit being taken by another selector of the same group and operating on the same multiple. The selectors for local calls are connected up by a hunting switch which is conveniently operated at the same time as the junction hunting switch and a digit which is to be absorbed causes the hunting switch to advance in search of a further local selector, its advance automatically releasing the first seized local selector from the connection. The normal speed of a single motion hunting switch being greater than the rotary speed of a two-motion selecting switch the former can easily search the number of outlets usually provided at a normal numerical switching stage in the inter-train pause. The chance of a call being lost due

to the hunting switch being unable to find another free selector need therefore never exceed the small value generally permitted at any normal switching stage and may in fact be less than this.

5 If desired, the hunting switch may be of the kind in which simultaneous search is carried out over two sets of wipers. The control of the hunting switch may be by a high speed test relay or relays. By the arrangements of the present invention all 10 the group selecting switches in the local exchange may be of the same type, i. e. ordinary group selectors.

The discriminating arrangements may comprise a digit switch and a set of control relays for 15 the various operations to be performed. Each digit as it is received is taken down on the digit switch until as many digits as may be required to determine the destination of the call have been recorded. Circuits are then completed for the 20 release of either the junction or the local selector. Until it is established that the call is not one to be completed over the junction the hunting switch giving access to the local selector is released after each digit and caused to step on in 25 search of another selector of the same group and the originally seized selector releases in its own time. Discrimination may be effected on any digit by the connection in a suitable manner of discriminating relays to contacts of a digit switch. It is 30 preferred that each digit received results in a connection over a different wiper of the digit switch and that the digit switch steps to a sub-normal position after each digit that does not determine the destination of the call.

35 If the call is to be completed over the junction, the local selector will be released as soon as determination has been made. In each case the discriminator is cut out of circuit as soon as determination is completed.

40 For the release from the connection of a selector following a digit that is to be absorbed and the seizure of a further selector to take the next digit the arrangements may provide for the temporary opening of the testing circuit of the selector hunting switch, thereby initiating the release of the selector, the test relay circuit being 45 restored before the removal of the busy potential from the test bank contact by the selector whereby the test relay is prevented from re-operating and a stepping circuit for the selector hunting switch is completed. The hunting switch may be of the dual testing type in which test is made simultaneously over two wipers and banks, in which case high speed test relays are preferably employed and on the restoration of the test

relay circuit the selector connected to the outlet in the other bank corresponding to that over which the released selector is connected may be seized, if free, without stepping action taking place.

Arrangements may be provided whereby the giving of a busy signal is delayed if congestion is met with at any stage until it has been determined that such congestion will prevent the completion of the connection. Thus failure to find a free junction does not prejudice the completion of a local call and in such case while a busy signal circuit and overflow metering circuit may be prepared they will only be completed when it has been determined that the call is to be extended over the junction. Similar conditions apply to the selector hunting switch. Furthermore failure by a local selector to find a free outlet in response to a digit to be absorbed is no bar to the successful completion of the call and transmission of busy signal is delayed until it has been determined that the setting of the selector is necessary for extension of the connection. An overflow meter may be provided for the selector hunting switch and the arrangements may be such that its circuit is not completed after the initial search or if the digit which would normally cause its operation is to be absorbed. These arrangements provide for the stepping of the hunting switch from an overflow position after unsuccessful search following a digit that is to be absorbed.

Reference will now be had to the accompanying drawings which show by way of example discriminating arrangements suitable for use at a satellite exchange. Fig. 1 of the drawings shows a discriminating repeater including 25-point single motion stepping switches as junction hunter and selector hunter, both switches being of the direct drive type and of the kind in which each outlet is tested in turn as the switch is stepped. Fig. 2 shows a modification of that part of Fig. 1 enclosed in a broken line rectangle in which the selector hunter is of the kind in which outlets are tested in pairs.

The circuits shown in Fig. 1 will first be described after which reference will be made to the modification shown in Fig. 2. The discriminating repeater of Fig. 1 may be considered as being situated at a satellite exchange and connected to outlets from a subscriber's preselector. It is also suitable for use at an exchange in which calls are received from a sub-satellite exchange. The repeater includes a transmission bridge with the usual impulse receiving relay A connected to the incoming side thereof and supervisory relays I and D bridged across the outgoing side thereof. The outgoing wires extend to a junction hunter which has outlets connected to junctions, the switch having a stepping magnet JHM and four wipers designated JH1—JH4. The outgoing wires from the bridge also extend to a 25-point selector hunter which has its outlets commoned in pairs so that the first 12 outlets numbered 1 to 12 are connected to local first selectors and the next 12 outlets numbered 13 to 24 are connected to the same local selectors as are outlets numbered 1 to 12. The switch has a stepping magnet SHM and four wipers designated SH1—SH4. All the local selectors connected to the selector hunter are in the same group so that a call for any local subscriber may be extended over any one of them. The 25th contact in each hunter is an overflow contact over which access is had to an overflow meter. There is also a

25-point reverse drive digit switch the contacts of which are also commoned in pairs, contacts 2 to 11 being commoned to contacts 13 to 22 respectively and connected as required to discriminating relays. The digit switch has a stepping magnet DSM and five wipers designated DS1—DS5. The switch has normal positions on the 1st and 12th contacts. The discriminating relays are designated DA, DB, LD and JD. Relays DA and DB by their operation at the end of a digit determine that the digit is to be absorbed, relay LD by its operation determines that the call is to be completed over the local selector and relay JD by its operation determines that the call is to be completed over a junction to the main exchange. The principal relays are the release relay B with its relief relay BA, metering relay J, all of the slow releasing type; dialling relay C, metering delay relay MD of the slow to operate type, the test relays KJ for the junction hunter and KS for the selector hunter and the auxiliary impulse repeating relay AA. The functions of the other relays will be apparent from the description as it proceeds.

The general operation of the repeater is as follows. When the repeater is taken into use, the junction and selector hunters search for and seize a free junction to the main exchange and a free local selector respectively. The first digit received at the repeater is repeated over the junction and to the local selector and is also registered by the digit switch. If this digit is such as to determine the route to be taken, one of the relays JD and LD will be operated and further impulses will be repeated directly over that route and the other route will be dropped and the digit switch cut out of circuit. If the digit does not determine the route, relay DA will be operated. The junction will be held but the seized selector will be released and the selector hunter will search for a further free local selector. The second digit is received and repeated in a similar manner to the first. If a third digit should be necessary to determine the route, relay DB will have been operated at the end of the second digit. The local selector seized as a result of the discriminating action in respect of the second digit is dropped and another seized and at the end of the impulse train of the third digit one or other route is dropped and further digits are transmitted over the route that is retained. Supervision and metering is effected in either case under control of the bridged relays D and I.

Up to the time that the digit that finally determines the route is received several possibilities of encountering an engaged condition exist. So that the existence of an engaged condition encountered during this time may not be prejudicial to the completion of the connection no busy signal is given until it is finally determined that it is not possible to extend the call over the required route. The conditions which may arise and which permit the delay and the final giving of an engaged signal if necessary will be made clear in the course of the detailed circuit description which now follows.

The repeater tests free by reason of the absence of earth from the incoming test wire p. When the repeater is taken into use, relay A operates over a preceding loop, in the example over the loop closed by the calling subscriber. Contact a1 closes operating circuits for relays B and AA and contact a2 closes in the wires out- 70 going from the feeding bridge. Relay B operates

and at contact *b1* connects earth to the incoming wire *p* to mark the circuit engaged. Contact *b2* operates relay BA, contact *b3* connects relays I and D to the outgoing side of the bridge and contact *b4* prepares the circuit of magnet DSM of the digit switch to receive impulses. Relay AA operates and at contact *aa1* closes a point in a loop circuit over resistance YE in the circuit for the local selector when seized. Relay BA operates and at contact *ba1* connects earth to the incoming *p* wire to substantiate that over contact *b1*. Contact *ba2* connects earth to a wire over which many of the relays are operated and held, contact *ba3* connects earth to one side of relay KJ, contact *ba4* connects the junction point of relay KJ and magnet JHM to wiper JH3, contact *ba5* connects the junction point of relay KS and magnet SHM to wiper SH3 and contact *ba6* opens a point in the homing circuit of the digit switch. If, when relay BA operates, the junction connected to the first contacts of the junction hunter on which the wipers will normally rest is free, earth will not be present on the contacts in the bank of wiper JH3 and magnet JHM will not operate. Relay KJ will operate however in a circuit from earth over contacts *ba3*, *le5*, winding of relay KJ, magnet contact *jhm*, magnet JHM to battery and the magnet will be disconnected from wiper JH3 at contact *kj2*. If, however, the wipers of the junction hunter are resting on contacts connected to a junction already engaged in a connection, earth will be present on the contact in the bank of wiper JH3 and relay KJ will be short-circuited. Magnet JHM will operate in a circuit from this earth over wiper JH3, contacts *le6*, *kj2*, *ba4*, *jhm*, and the magnet to battery and by the interruption of its own circuit at contact *jhm* the magnet will step the switch until contacts connected to a free junction are reached whereupon there being no earth over wiper JH3 magnet JHM will not re-operate but relay KJ will operate, disconnect the magnet at contact *kj2* and at the same contact apply earth to wiper JH3 to guard the junction against seizure by another testing switch. Contact *kj1* opens the homing circuit of the junction hunter and contacts *kj3* and *kj4* switch the speaking wires through to the junction over wipers JH1 and JH2.

A similar operation takes place at the selector hunter. On the change-over of contact *ba5*, a driving circuit for magnet SHM is prepared and if the contacts on which the wipers are standing are connected to an engaged outlet, the driving circuit will be completed over wiper SH3 to earth on the bank contact of engaged outlets. The switch will be stepped until a free outlet is encountered whereupon, there being no earth on the bank contact of wiper SH3, the magnet will not be energised. Relay KS which during stepping is short-circuited by the busy earth now operates from earth over contacts *ba2*, *da4* and *jd7* in series with magnet SHM and at contact *ks2* opens the stepping circuit and applies earth to the test wiper SH3 to engage the outlet. Contacts *ks3* and *ks4* switch the speaking wires through to the seized selector over wipers SH1 and SH2 and a loop to the selector is closed over contact *aa1* and resistance YE.

When both hunting switches have found free outlets and relays KJ and KS are both operated, dial tone is connected over wire DT, contacts *ks5*, *kj5*, *le3*, *ig3* and the right-hand winding of relay I whence it is relayed by induction to the in-

coming speaking wires. Meanwhile relay J has operated in a circuit from earth over contacts *ba2*, *jd3*, *le1* and *md1*. At contact *ji1* relay J locks up, at contact *ji2* the metering circuit is prepared and at contact *ji3* the supervisory lamp SL is lit over contacts *ig2*, *jd4* and *le2* and a battery connected alarm relay. Also, consequent on the seizure of a junction, relay I is operated over the junction and at contact *ii1* connects a holding earth to relay BA and at contact *ii2* opens a point in the busy tone circuit over wire BT.

It may here be convenient to refer to busy conditions that may be encountered at this stage. Should either of the hunting switches fail to find a free outlet they are stepped to their 25th contacts where, there being no connection at this time they are brought to rest and relays KJ and KS are operated. These contacts in the bank of wipers JH1 and JH2 are not connected so that relay I will not be operated. The bridge is, at this stage, disconnected from the selector hunter at contacts of relay LD. As neither relay JD nor LE is as yet operated busy tone over wire BT and contact *i2* will not reach the caller.

The caller having heard dialling tone may now commence to dial the wanted number. The impulses of the first digit are received by relay A and are repeated at contact *a1* to relay AA, and magnet DSM and at contact *a2* over the junction, if a free junction has been seized as will be assumed. At the first release of relay A, relay AA will release and repeat the impulse to the seized local selector at contact *aa1*, (it will be assumed that a local selector has been seized) a loop existing over resistance YE. At the back contact *a1*, a circuit is now closed from earth over contacts *a1*, *b4*, *le4*, *jd6*, magnet DSM to battery and the magnet is energised. A parallel circuit is also closed over contacts *a1*, *b4* and *ig1* for relay JG. This relay operates and locks over contacts *ig1*, *kj6* and *ba2*. At contact *ig2* it opens the circuit of lamp SL and at contact *ig3* it opens the dial tone circuit. In another parallel circuit relay C operates and short-circuits its low resistance winding at contact *c1* to render the relay slow to release so that it holds up during impulse transmission. Contact *c2* opens to guard against a false operation of a discriminating relay and contact *c3* closes a low impedance bridge across the outgoing speaking wires. On the re-operation of relay A, relay AA re-operates and the circuit of magnet DSM being opened the digit switch is stepped to its first contacts. Subsequent impulses are repeated in a like manner over the junction and to the local selector and digit switch. After the last impulse, relay A remains steadily operated and relay C releases. Contact *c2* closing, a circuit is closed from earth over contacts *ba2*, *ld5*, *jd2*, *c2*, *da2*, wiper DS3 for one of the discriminating relays. Relay I is operated over the junction. If this digit determines the route then the other route seized is dropped and the digit switch cut out of circuit. If it does not determine the route then the digit switch responds to a subsequent digit. If the call is to proceed over a junction it will probably be determined by the first digit but the arrangements provide for its determination by any of the first three digits.

Assuming that the first digit determines the call to be one for completion over the junction to the main exchange, the circuit closed over wiper DS3 will include relay JD and that relay will be operated and will lock up over contacts *jd1* and *ba2*. Contact *jd2* opens the circuit over 75 the digit switch wipers to prevent operation of

any of the discriminating relays while the switch is homing, contact *jd3* opens the operating circuit of relay *J*, contact *jd4* opens a point in the circuit of lamp *SL*, contact *jd5* closes to prepare for the transmission of busy tone should an engaged condition be encountered by the junction hunter, contact *jd6* disconnects magnet *DSM* from the impulse repeating circuit and connects it in a homing circuit over contact *dsm* and wiper *DS1*, contact *jd1* releases relay *KS* thereby releasing the seized local selector and contact *jd8* connects the 25th contact in the bank of wiper *JH3* to an overflow meter for the operation of the latter should no junction have been seized by the junction hunter in its search. As a consequence of the release of relay *KS*, the speaking wire circuit over wipers *SH1* and *SH2* is opened to initiate the release of the seized local selector and until the release relay of the selector releases the earth on the test bank contact applied by it is extended back over wiper *SH3*, contacts *ks2*, *ba5*, *shm* and magnet *SHM*. The magnet operates and steps the selector hunter to the next contacts. If these contacts are busy the selector hunter will step and continue stepping until free contacts are found or the last contacts reached. These movements are however without effect as the circuit of relay *KS* being open at contacts *jd1* the contacts on which the switch rests will not be engaged by it.

Further impulse trains from the subscriber's dial are repeated over the junction at contact *a2* until the connection has been completely set up.

If the first digit does not determine the route, relay *DA* will be operated instead of relay *JD* as described above and will lock up over contacts *da1* and *ba2*. Contact *da2* opens in the circuit over wiper *DS3* for the discriminating relays, contact *da3* closes the homing circuit for the digit switch over wiper *DS1*, contacts *dsm* and *oa4* and magnet *DSM*, contact *da4* closes an operating circuit over contact *oa3* for relay *CT*, which is slow to operate to give time for the release of relay *KS*, and releases relay *KS* and contact *da5* connects the right hand winding of relay *OA* to the normal contacts in the bank of wiper *DS2*. The digit switch drives to its next normal position in which relay *OA* is operated in the above described circuit. Relay *CT* on operating re-connects relay *KS* at contact *ct1*. When relay *KS* released the local selector was released and the selector hunter stepped on as described in connection with the operation taking place when the first digit denotes a junction call but in this case when a free outlet is encountered, relay *KS* re-operates over contacts *ct1* and *ba2*, (relay *JD* being unoperated) and engages the outlet and switches the speaking circuit through. Before coming to rest on the 25th contact position if no free selector has been found the selector hunter will test all the outlets, that is the remainder of those numbered 1 to 12 and all of those numbered 13 to 24. No busy signal is given in the last contact position as relay *LE* has not been operated and relay *JG* is operated and the final route of the call has not yet been determined. When relay *OA* operates, it locks over contacts *oa1* and *ba2*, at contacts *oa2* connects wiper *DS4* to the discriminating circuit, at contact *oa3* releases relay *CT* and holds relay *KS* over contacts *db4* and *da4*, at contacts *oa4* opens the homing circuit and at contact *oa5* connects the normal contacts in the bank of wiper *DS2* to a circuit for relay *OB*.

The second digit is repeated like the first over the junction, to a local selector and to the digit

switch which is set accordingly, relay *C* being operated during the impulse train. At the end of the impulse train, relay *C* releases and at contact *c2* extends earth over wiper *DS4* to the discriminating relay connected up by the digit switch. If this digit does not determine the route to be taken, relay *DB* will be operated and locked over contact *db1*. Contact *db2* opens the circuit over wiper *DS4*, contact *db3* closes a homing circuit for the digit switch, contact *db4* releases relay *KS* and closes a circuit for relay *CT* over contacts *ob3*, *oa3* and *da4* and contact *db5* connects the left-hand winding of relay *OB* over contacts *oa5* to the normal contacts in the bank of wiper *DS2*. The digit switch homes, the magnet circuit being over contacts *ob4* and *db3* and relay *KS* is released thereby releasing the local selector and closing the stepping circuit for the magnet *SHM* in the manner described earlier. When the digit switch reaches a normal position, relay *OB* is operated by means of its left-hand winding and locks up over its right-hand winding and contacts *ob1* and *ba2*. Contact *ob2* connects up wiper *DS5* in the discriminating circuit, contact *ob3* releases relay *CT* and re-connects relay *KS* over contacts *db4*, *oa3* and *da4* and contact *ob4* opens the homing circuit of the digit switch. Relay *KS* operates when the selector hunter has found a free selector to respond to the third digit.

The arrangements of the present example are provided for discrimination on any one of three digits so that since no determination of route has been effected by either of the first two digits, such determination must be made at the end of the third digit. If the call is to be completed over the local selector, relay *LD* will be operated over wiper *DS5* at the end of the third impulse train and will lock up over contact *ld1*. The operations which follow are the same whether relay *LD* is operated by the third or any earlier digit except that in one case relays *DA* and *OA* with or without *DB* and *OB* are operated and in the other case they are not. When relay *LD* operates, it closes the circuit of relay *LE* at contact *ld2*, connects wipers *SH1* and *SH2* to the feeding bridge and disconnects resistance *YE* at contacts *ld3* and *ld4*, opens the operating circuit for the discriminating relays at contact *ld5* and holds relay *AA* operated at contact *ld6*. Relay *LE* operates; at contact *le1* opens a point in the operating circuit for relay *J*, at contact *le2* opens a further point in the circuit for lamp *SL*, at contact *le3* prepares a circuit for the transmission of busy tone, at contacts *le4* disconnects magnet *DSM* from the impulse repeating circuit and closes the homing circuit of the digit switch, at contact *le5* releases relay *KJ* and at contact *le6* maintains the engaged marking of the junction and holds open the operating circuit of magnet *JHM*. Contact *le7* connects the last contacts in the bank of wiper *SH3* to an overflow meter this circuit being completed should no free selector have been found by the selector hunter to take the third or other digit. In this latter event the overflow meter will be operated and on the release of relay *JG* the busy tone circuit will be completed over wire *BT*, contacts *i2*, *le3*, *jg3* and the right-hand winding of relay *I* and relayed by induction to the caller. By the release of relay *JG* the engaged marking is removed from the junction at contact *jg4* and by the release of relay *KJ* which occurs before that of relay *JG* the junction is disconnected and free for other use by the opening of contacts *k3* and *k4*. Further impulses for the setting of local selector switches are repeated at contact *a2* over

the loop closed over contacts *c3* and the selector hunter wipers, contact *aa1* remaining closed by reason of relay AA being held over contact *ld6*. It may be noticed that relays LE and JD perform similar functions for a local and junction call respectively. If the second or third digit had caused operation of relay JD, the subsequent operations would have been the same as those described earlier in the case of the first digit determining that the call was to proceed over the junction to the main exchange.

When the called subscriber replies, relay D is operated either over the junction or over the local selector as the case may be and at contact *d1* operates relay MD. Contact *d2* in conjunction with contacts *j5* guards the outgoing circuit against a flick of relay A during the subsequent reversal of current through relay A for the repetition of the answering supervisory signal which would be necessary if the call had been received from a sub-satellite or adjacent exchange. Contact *md1* disconnects relay J initiating its release, contact *md2* disconnects the direct earth from the incoming test wire *p*, contact *md3* applies positive battery thereto for metering purpose during the release period of relay J, contacts *md4* and *md5* reverse the direction of current over the incoming wires for the supervision and metering of the call should it have come from another exchange and connect a ballast resistance BR in the incoming line circuit and contact *md6* opens to guard against lighting of the supervisory lamps SL on the subsequent release of relay J. After an interval relay J releases, terminates the metering pulse at contact *j2* and at contact *j5* removes the guard circuit from contact *a1*.

At the end of the conversation the caller will clear and relay A will release. Relays JG and C will operate over contact *a1* but without effect and the outgoing circuit will be opened at contact *a2*. Shortly after, relay B will release and in turn will release relay BA. Relay BA on releasing disconnects the holding earths for all the relays now held and they will release in their own time. By the relapse of contact *ba4* the homing circuit of the junction hunter is closed from earth over commoned off-normal contacts and wiper JH4, contacts *kj1*, *ba4*, *jhm* and magnet JHM and the hunter is restored to its first contact position in which it will rest with its wipers on the first contacts connected to outgoing junctions. At contact *ba5* a similar homing circuit will be closed over wiper SH4, contacts *ks1*, *ba5*, *shm* and magnet SHM and the selector hunter is restored to its first contact position in which its wipers rest on contacts connected to a local first selector. Relays I and D release consequent on the opening of contact *a2* and the other relays consequent on the opening of contact *ba2*. Contacts *b1* and *ba1* disconnect the engaging earth from the incoming test wire *p*. If the called subscriber clears first, relays D and I will release. Release of relay D releases relay MD at contact *d1* and consequent on the relapse of contact *md6*, lamp SL will glow in a circuit over contacts *le2*, *md6* and *j3* if the call had been a local one or over contacts *le2*, *jd4*, *md6* and *j3* if the call had been made over a junction. Reversal to normal of current over the incoming wires will take place at contacts *md4* and *md5* to repeat the release condition to a preceding feeding bridge should there be one in the connection.

If a call is made to a manual switchboard position, the caller may clear after he has been

answered and in that case a steady battery connection is made to the positive wire at the switchboard end of the line. When the caller cleared relays A and B released and the negative junction wire was opened at contact *a2*. Relay I is however held from earth over contacts *j4* and *b3* to battery on the positive wire and relay BA remains held and the busy marking of the circuit maintained by earth over contact *ba1* to wire *p* and the caller's line is held. Release follows when the operator clears and the battery potential is disconnected from the positive wire. Relay I releases, releasing relay BA and release of the other relays follows in the manner described earlier.

Reference will now be made to Fig. 2. The figure shows a selector hunter arranged for dual testing and the circuits shown therein should be substituted for those enclosed in the broken line rectangle in Fig. 1 to form a complete repeater. However, as the circuits of Fig. 1 have been fully described it is thought that a description of the modified operations due to the change of selector hunter will be sufficient for the understanding of the modification. The selector hunter of Fig. 2 is shown as a 25-point stepping switch with two sets of 4 wipers and contact banks the contacts *1* to *10* and *13* to *22* in each bank being commoned to the same set of outlets so that 20 outlets are actually available. Only the testing and homing wipers of the switch are shown and these are designated SH3A and SH3B and SH4 to correspond to wipers SH3 and SH4 of Fig. 1. There is also an additional wiper SH5 and bank of contacts for dealing with congestion conditions. It is to be understood that there will be two pairs of speaking wire wipers connected to the feeding bridge over suitably disposed contacts of the switching relays KSA and KSB in place of contacts *ks3* and *ks4* of Fig. 1, their contact banks being connected to local first selectors from contacts *1* to *10* and *13* to *22* in the manner shown for the outlet connections from the banks of wipers SH3A and SH3B. The stepping magnet is designated SHM and associated with the switch are two high speed test relays TA and TB, the former for testing the outlets over wiper SH3A and the latter for testing the outlets over wiper SH3B. In the bank of wiper SH3A contacts *11*, *23* and *24* are earthed and contacts *12* and *25* are last contact or overflow positions. In the bank of wiper SH3B contacts *11*, *12*, *23*, *24* and *25* are earthed, a relay OF is provided for connecting contact *12* in the bank of wiper SH3A to the overflow meter when necessary and for stepping the hunter from the 12th contact overflow position. Additional contacts of relays B, BA, and LD, DA and DB of Fig. 1 are shown and it is to be understood that contacts of relays KSA and KSB will be connected in place of contacts *ks5* in Fig. 1.

The operations when the discriminator is taken into use are as follows. When relays B and BA operate, earth is connected over contact *jd1* and contacts *ksb4* and *ksa4* to relays TA and TB respectively. Contacts *ba5* and *ba1* will also be closed so that if the outlets on which the switch is standing, that is, the first outlets as shown in the drawings, are both engaged, earth potential will be present on the contacts and relays TA and TB will not operate. If only one of the contacts is earthed, then the relay connected to the unearthing contact will operate to the locally connected battery. If neither contact is earthed, both relays will operate but contact *ta1* will connect delay KSA to earth over contact *jd1* and dis-

connect the circuit for relay KSB over the front contact *tb1* so that relay KSB will not be operated. The operation of relay KSA opens the circuit for relay TB at contact *ksa4* so that relay TB is released. In this way preference is given to the outlet in the A banks if like outlets from both banks are free. Let it be assumed that the first outlets are both engaged. When contacts *ba5* and *ba2* (Fig. 2) are operated, a circuit is completed from earth over contacts *jd1*, *ta1*, *tb1*, *ba5*, *shm*, and magnet SHM to battery. The magnet energizes, steps the wipers to the second contacts, opens its driving circuit at contact *shm* and releases. If the second contacts are both engaged, neither relay TA nor relay TB will be operated and the magnet operates to step the wipers to the third contacts. Stepping continues in this manner until a free contact in one of the pairs of banks is encountered. If a free outlet is found in the A bank and the corresponding outlet in the B bank is engaged, relay TA operates and at contact *ta1* opens the magnet circuit and closes the circuit for relay KSA. Relay KSA operates. At contact *ksa1* the homing circuit is opened, at contact *ksa2* relay TA is disconnected from wiper SH3A and earth is connected thereto to engage the outlet, at contact *ksa3* relay TB is disconnected from wiper SH3B, at contact *ksa4* relay TB is disconnected from the earth over contact *jd1* and other contacts connect the speaking wire wipers to the transmission bridge and close in the dial tone circuit. Had the free outlet been found in the B bank and the corresponding outlet in the A bank was engaged, relay TB would have operated to open the magnet circuit and connect up relay KSB. Relay KSB on operating performs similar functions to relay KSA, engaging the outlet over contact *ksb2* and disconnecting relay TA at contacts *ksb3* and *ksb4*.

If the first digit received at the repeater does not determine the route, relay DA (Fig. 1) is operated and relay KSA or KSB as the case may be is released and the selector impulse relay releases. For convenience of description it will be assumed that the selector was connected to the A bank. The earth applied to the test bank contact by the selector release relay is maintained during the release lag of that relay and relay TA is released. If the corresponding outlet in the B bank is free, relay TB will operate and the selector connected to the outlets in the B bank will be seized and engaged and relay KSB will be operated. Should, however, this outlet be also engaged the magnet circuit will be re-closed on the release of relay TA and search for a free selector to take the second digit will be made. If the second digit does not determine the route to be taken, relay DB (Fig. 1) will operate and the selector hunter test relay and the seized selector will be released and the selector hunter will hunt for, if necessary, a further selector to take the third digit. If the third or either preceding digit determines that the call is to be completed over a junction, relay JD (Fig. 1) will be operated and contact *jd1* opens the circuits of the operated test and switching relays releasing the local selector, leaving the selector hunter on the contacts to which it was last set. If, during its search for a free selector, contacts 11, 23 or 24 are reached the hunter is stepped on as for a busy outlet to contacts 12 or 25 as the case may be. Closure of contact *da6* or *db6* will complete a stepping circuit for the magnet to step the switch to contacts 13 or 1 respectively. In the bank of wiper SH5

contacts 13 to 25 are connected together and to relay OF so that when the switch is stepped to any of these contacts relay OF is operated and locked up over contact *of1* to earth over contact *ba2* (Fig. 1).

In the case of the preliminary seizure, search will continue in the normal manner and if congestion is encountered the switch will be stopped on contacts 12 by the operation of relay TA owing to absence of earth over wiper SH3A. If the first digit is to be absorbed failure to record the digit on a selector will be of no consequence. When the first digit has been received, contact *da6* will be changed over if the digit is to be absorbed. TA will be released due to the disconnection of earth over contact *jd1* and when this earth is subsequently re-applied, relay TA will be short-circuited over wiper SH3A, contact 12 and contacts *of2* and *da6* and search will commence for a free selector over contacts 13 to 22. Should a state of congestion be encountered at this stage the switch will be stopped on contacts 25 and if the second digit is to be absorbed, contact *db6* will be changed over to prevent re-operation of relay TA after the earth over contact *jd1* has been re-applied following its removal by the operation of relay DB (Fig. 1). The switch will then search for a selector to take the third digit. When the switch reached contacts 13, relay OF was operated so that when it again reaches contact 12 it is stopped owing to the absence of earth on this contact in the bank of wiper SH3A due to contact *of2* in its front position. If this search had started from one of the contacts 13 to 22 it would have continued over contact 25 earthed over contact *db6* until the 12th contacts were reached. When it is determined that the call is to proceed over a local selector, relay LD (Fig. 1) will be operated and if the selector hunter has failed to find a free selector to take the route determining digit, it will be standing on contacts 25 or 12 and a circuit for the overflow meter will be closed over contacts *ksa2*, *ba5*, wiper SH3A, contact *db6* or *of2*, contact *jd1* and overflow meter to battery and the congested condition will be recorded. The caller will receive busy tone as described in connection with Fig. 1. When the connection is finally cleared, the disconnection of earth from contact *jd1* releases the operated test and switching relays and the locking circuit of relay OF is also opened and that relay released if it has been previously operated. Relays B and BA (Fig. 1) being now released the homing circuit for the selector hunter is closed from earth over the homing bank and wiper SH4, contacts *ksb1*, *ksa1*, *b5*, *shm*, magnet SHM and the magnet steps the switch by self-drive action to its first contact position which is unconnected in the homing bank and the hunter is brought to rest.

What we claim as new and desire to secure by Letters Patent is:

1. In a digit absorbing repeater, a plurality of outgoing lines, means operated responsive to the seizure of said repeater for seizing an idle one of said lines, means for receiving impulses indicative of any value of digit, means for repeating said impulses over the seized line, and means operated responsive to the completion of said reception and repetition of impulses, if the digit indicated thereby is of a predetermined value, to release said seized line and automatically seize another idle one of said lines.

2. In a digit absorbing repeater, a plurality of lines, a switch having access to said lines, means operated responsive to the seizure of said repeater

for causing said switch to search for and seize any idle one of said lines, means for receiving impulses indicative of any value of digit, means for repeating said impulses over the seized line, and means effective after said reception and repetition of impulses, if the digit indicated thereby is of a predetermined value, for causing said switch to automatically release said one line and to search for and seize any other idle one of said lines, said third means then effective to repeat over said other line impulses subsequently received by said second means.

3. In a discriminating unit, means for receiving a particular order of digit in a multi-digit number, two groups of lines, means for seizing an idle line in each of said groups before said first means has completed its reception of said particular order of digit, and means controlled by said digit when its reception is complete, if said digit is of a predetermined value, for releasing one of the seized lines without releasing the other and seizing another idle line in the same group as the released line.

4. In an automatic telephone system wherein, during the extension of a connection through a plurality of successive switching stages, a repeater at one of said stages receives a succession of digits and normally repeats them to one of a plurality of switches which make up a single subsequent switching stage, means in said repeater operated after the reception and repetition of one of said digits, if that digit is of a predetermined value, to release said one switch and condition another one of said switches to receive digits, said repeater then effective to repeat at least part the remainder of said succession of digits, when received, to said other switch.

5. In a telephone system wherein, during the extension of a call, a discriminating unit at a particular stage of the connection receives call directing impulses and determines therefrom whether the call is a local call or an outgoing call, and wherein said unit, until it completes such determination, repeats said impulses to one of a plurality of local switches making up the next switching stage and also repeats them over an outgoing trunk line, means in said unit controlled by the received call directing impulses at times to release the local switch to which it has been repeating said impulses, said means effective at such times to cause said unit thereafter to repeat call directing impulses subsequently received during the extension of the same call to a different one of said local switches.

6. In a telephone system, a repeater in one exchange having access to a trunk line outgoing to another exchange and also having access to a plurality of local trunk lines, means in said repeater for seizing said outgoing trunk line and one of said local trunk lines, said repeater then effective to receive call directing impulses and repeat them over both of the seized trunk lines, means controlled by said impulses for causing said repeater to release said outgoing trunk line if the impulses are indicative of a call to said one exchange and to release the seized local trunk line if the impulses are indicative of a call to said other exchange, means at times controlled by said impulses for causing said repeater to release the seized local trunk line without releasing the outgoing trunk line and immediately to seize another local trunk line, said repeater thereafter effective to repeat the received impulses over said outgoing trunk line and said other local trunk line.

7. In a digit absorbing repeater, a plurality of lines, a switch having access to said lines and also to an overflow position, means operated responsive to the seizure of said repeater for causing said switch to search for an idle one of said lines, said switch effective to move to said overflow position if no idle line is found, means effective when said switch occupies said overflow position for receiving impulses indicative of any digit, means operated after said reception of impulses, if the digit indicated thereby is of a predetermined value, to cause said switch to leave said overflow position and again search for an idle one of said lines, means effective if an idle line is found on said last search to seize such idle line, and means for repeating impulses subsequently received by said second means over the seized line.

8. In a digit absorbing repeater, a plurality of lines, a switch having access to said lines and also to an overflow position, means operated responsive to the seizure of said repeater for causing said switch to search for an idle one of said lines, said switch effective to move to said overflow position if no idle line is found, means effective when said switch occupies said overflow position for receiving impulses indicative of any digit, means operated after said reception of impulses, if the digit indicated thereby is of a predetermined value, to transmit a busy signal, other means operated after said reception of impulses, if the digit indicated thereby is of a different predetermined value, to cause said switch to leave said overflow position and again search for an idle one of said lines, means effective if an idle line is found on said last search to seize such idle line, and means for repeating impulses subsequently received by said second means over the seized line.

9. In a telephone system, a trunk line outgoing from one exchange to another, a plurality of trunk lines local to said one exchange, a switch having access to said local trunk lines, discriminating apparatus in said one exchange, means responsive to a seizure of said apparatus for seizing said outgoing line and for causing said switch to search for an idle local line, means for seizing any idle local line found by said switch, means in said apparatus for receiving impulses and determining whether they are indicative of a desired connection local to said one exchange or a desired connection outgoing from said one exchange to said other exchange, means in said apparatus at times controlled by said impulses before said determination is complete for causing said switch to repeat its search for an idle local line, and means in said apparatus effective at such times responsive to the completion of said determination if same reveals that the received impulses are indicative of a desired local connection for transmitting a busy signal only if said switch has failed to find an idle local line on its last search before the completion of said determination.

10. In a telephone system, two switches each having access to a different group of lines, apparatus for receiving impulses indicative of desired connections over both of said groups, means responsive to a seizure of said apparatus for operating each of said switches to search for and seize an idle line in its respective group, means in said apparatus for identifying, from the impulses thereafter received, the group over which a connection is desired, means in said apparatus at times controlled by said impulse before said

identification is complete to cause one of said switches to search a second time for an idle line in the group accessible to it and to seize any idle line found during said second search, means effective upon conclusion of said identification for causing the one of said switches having access to the group over which a connection is not desired to release the line which at that time is seized by it, and other means effective upon conclusion of said identification to transmit a busy signal only if the one of said switches having access to the group over which a connection is desired has failed to find an idle line in that group.

11. In a telephone system, two switches each having access to a different group of lines, apparatus for receiving impulses indicative of desired connections over both of said groups, means responsive to a seizure of said apparatus for operating each of said switches to search for and seize an idle line in its respective group, means in said apparatus for identifying, from the impulses thereafter received, the group over which a connection is desired, means effective upon conclusion of such identification for causing the switch having access to the group over which a connection is not desired to release the line seized by it, and other means effective upon conclusion of such identification to transmit a busy signal only if the one of said switches having access to the group over which a connection is

desired has failed to find an idle line in that group.

12. In a telephone system wherein each of a plurality of lines becomes characterized as busy 5 responsive to its seizure and becomes characterized as idle responsive to its release, a switch having access to all of said lines, means for causing said switch to start searching for an idle one of said lines, means in said switch for testing each of said lines in turn during said search, said testing means effective to control said switch in accordance with the characterization of each line tested whereby said search is continued in response to each test of a line characterized as busy and is halted in response to the test of any line characterized as idle, means for seizing any idle line which causes said search to be halted, means for preventing said testing means from causing said switch to resume its search when the seized line becomes characterized as busy responsive to such seizure, means for subsequently releasing the seized line, said last means effective to disable said preventing means before the released line becomes characterized as idle responsive to such release, whereby said testing means is effective to control said switch to resume its search in accordance with the temporary characterization of said released line as busy.

DAVID ADAM CHRISTIAN.

WILLIAM HENRY JOSEPH DIBBEN.
